BAFFLE TYPE MUFFLER WITH PLURAL EXPANSION CHAMBERS

Peter A. Lievense and Harry T. Phillips,
Jackson, Mich.

Application August 25, 1949, Serial No. 112,323

9 Claims. (Cl. 181—57)

1

This invention relates to improvements in baffle type muffler with plural expansion chambers.

The principal objects of this invention are:

First, to provide a muffler for silencing the exhaust of internal combustion engines which muffler is extremely effective and inexpensive to construct.

Second, to provide a muffler of small diameter so as to require a minimum of vertical space beneath a vehicle.

Third, to provide a muffler which requires no outer body or casing.

Fourth, to provide a muffler which eliminates back pressure on the internal combustion engine.

Fifth, to provide a muffler which is entirely self-sustaining and requires support only at its ends where it is connected to the exhaust pipe of an engine and the tail pipe of an automobile.

Other objects and advantages relative to details of our invention will be apparent from a consideration of the following description and claims.

The drawings, of which there is one sheet, illustrate a preferred form of our muffler.

Fig. 1 is a fragmentary elevational view of the muffler partially broken away in longitudinal cross section.

Fig. 2 is a transverse cross sectional view through one section of the muffler taken along the plane of line 2—2 of Fig. 1.

Our muffler consists of a series of similar body elements joined together to form an elongated muffler structure. It should be understood that as many of the body elements are used as are required to adapt the muffler to the type of engine. We have found that for the average automobile engine of eight cylinders, between six and eight of the body elements connected in series provide satisfactory muffling action.

Each body element consists of a straight cylindrical portion 2 joined with and merging into an expanding forwardly tapering conical portion 3. The end of the cylindrical portion is closed by a wall 4 which is secured by welding as at 5. The wall of the cylindrical portion is provided with a plurality of uniformly positioned apertures 6. The sum of the areas of the apertures 6 is at least equal to the cross sectional area of the cylindrical portion 2.

The cylindrical portion 2A of the first body element 1 is arranged to receive the end of the exhaust pipe 7 of an internal combustion engine. The muffler is conveniently supported at its

2

forward end by attachment to the exhaust pipe which is in turn supported in any suitable fashion. The cylindrical portion of the next succeeding body element is disposed through the rear wall 8 of the preceding element and concentrically supported within the conical portion 3 of the preceding body element, the joints being made gas-tight by welding as at 9. It will be noted that the inner end of the cylindrical portion 2 is thus located in spaced relationship with the inside of the conical portion 3 midway of the length of the latter, thus forming an annular space 10, the cross sectional area of which is considerably smaller than the cross sectional area of the cylindrical portion 2.

Each of the several body elements 1 are joined successively to the preceding body element as just described until the final body element, which is connected to the tail pipe 11. Preferably the tail pipe is provided with a cylindrical portion 12 nesting within the final body element in the same manner as the cylindrical portion of the body element and is sealed to the conical end of the final body element by the annular wall 13.

The foregoing construction provides a series of cylindrical chambers of approximately the same cross sectional area as the area of the exhaust pipe. Each cylindrical chamber opens to an expanding conical chamber with an annular constricted passage at its end opening to the wall of the next succeeding cylindrical chamber. Thus the exhaust gases are caused to pass repeatedly through a passage which may be referred to as normal size, being equal to the size of the exhaust pipe, and then expand slightly into the conical passage, after which they are constricted before re-expanding into a successive passage of normal size. This action of the gases has been found to effectively muffle the noises of the exhaust without creating back pressure on the internal combustion engine.

All joints in the muffler are easily made by external welding operations as the end plugs 4 are installed prior to assembly of the body elements. The muffler is of small cross section so that it does not project very far below an automobile body and is thus not liable to be torn off by obstructions in the road. No external housing or jacket is required for the muffler, thus further reducing the cost of manufacture.

Having thus described our invention, what we claim as new and desire to secure by Letters Patent is:

1. A muffler for internal combustion engines comprising a series of body elements, each of said

elements having a cylindrical leading portion merging into an outwardly diverging conical portion, the cylindrical portion of each succeeding body element being centrally disposed within the conical portion of the preceding body element with its inner end spaced from the wall of the conical portion to form therewith an annular passage of smaller cross sectional area than the area of said cylindrical portion, the sides of each succeeding cylindrical portion forming openings of cross sectional area at least equal to the cross sectional area of the cylindrical portion, a wall closing the inner end of each succeeding cylindrical portion, and annular walls joining the divergent ends of each conical portion to the outsides of the cylindrical portions of each succeeding body element, said body elements being joined in mutually self supporting fashion and having the exterior of their conical portions exposed to the atmosphere.

2. A muffler for internal combustion engines comprising a series of body elements, each of said elements having a cylindrical leading portion merging into an outwardly diverging conical portion, the cylindrical portion of each succeeding body element being disposed within the conical portion of the preceding body element with its inner end spaced from the wall of the conical portion to form therewith an annular passage of smaller cross sectional area than the area of said cylindrical portion, the sides of each succeeding cylindrical portion forming openings, a wall closing the inner end of each succeeding cylindrical portion, and annular walls joining the divergent ends of each conical portion to the outsides of the cylindrical portions of each succeeding body element.

3. A muffler for internal combustion engines comprising a series of body elements, each of said elements having a cylindrical leading portion merging into an outwardly diverging conical portion, the cylindrical portion of each succeeding body element being disposed within the conical portion of the preceding body element with its inner end spaced from the wall of the conical portion to form therewith an annular passage, the sides of each succeeding cylindrical portion forming openings, a wall closing the inner end of each succeeding cylindrical portion, and annular walls joining the divergent ends of each conical portion to the outsides of the succeeding body element.

4. A muffler for internal combustion engines comprising a series of body elements, each of said elements having a tubular gas entrance portion merging into an outwardly diverging portion, the tubular portion of each succeeding body element being disposed within the diverging portion of the preceding body element with its inner end spaced from the wall of the diverging portion to form an annular passage of smaller cross sectional area than the area of said tubular portion, the sides of each succeeding tubular portion forming openings of cross sectional area at least equal to the cross sectional area of the tubular portion, a wall closing the inner end of each succeeding tubular portion, and annular walls joining the divergent ends of each diverging portion to the outsides of the tubular portion of each succeeding body element.

5. A muffler for internal combustion engines comprising a series of body elements, each of said elements having a tubular gas entrance portion merging into an outwardly diverging portion, the tubular portion of each succeeding body ele-

ment being disposed centrally within the diverging portion of the preceding body element with its inner end spaced from the wall of the diverging portion to form an annular passage, the sides

5 of each succeeding tubular portion forming openings, a wall closing the inner end of each succeeding tubular portion, and annular walls joining the divergent ends of each diverging portion to the outsides of the succeeding body element.

10 6. A muffler for internal combustion engines comprising an aligned series of body elements, each element comprising a cylindrical front portion merging into an outwardly diverging conical rear portion of substantially greater diameter at its rear end than the cylindrical portion, the cylindrical portion being closed at its front end and having a plurality of openings in its side wall, and end walls for the rear end of said elements, the cylindrical portions of one ele-

15 20 ment being disposed through the rear wall of the preceding element concentrically of the conical portion of the preceding element and with its side wall openings opening into the preceding element, the relative diameters of the cylindrical portions and the conical portions being such that there is an annular space around each cylindrical portion, the elements being connected and supported by said rear walls in a unitary assembly.

25 30 7. A muffler for internal combustion engines comprising an aligned series of body elements, each having a cylindrical front portion and an outwardly diverging conical rear portion merging into the front portion and of substantially greater diameter at its rear end than the cylindrical portion, and end walls for the rear ends of the elements, the cylindrical portion of one element being arranged through and supported concentrically within the conical portion of the preceding element, the cylindrical portion being closed at its forward end and having openings in its side wall opening to the annular space surrounding the cylindrical portions, which space is open to the preceding element, the elements

35 40 45 coaxing to provide a series of connected expansion chambers.

8. A muffler for internal combustion engines comprising a series of body elements having connected tubular inlet portions and outwardly tapering expansion chamber portions, succeeding elements of the series being arranged with their inlet portions concentrically within the large ends of the expansion chamber portions of preceding elements, each preceding element having an end wall across the large end of its expansion chamber portion through which the inlet portion of the next succeeding element is disposed and secured, there being an annular space between the inlet portions and the surrounding

50 55 60 65 expansion chamber portions, the forward end of each succeeding inlet portion being closed, the side walls of said inlet portions being provided with a plurality of inlet openings, said end walls constituting the only supporting connection between the elements, the interiors of the elements being unobstructed except as obstructed by said inlet portions.

9. A muffler for internal combustion engines comprising a series of body elements having connected tubular inlet portions and outwardly tapering expansion chamber portions, succeeding elements of the series being arranged with their inlet portions concentrically within the large ends of the expansion chamber portions of preceding elements, each preceding element having

70 75 76

an end wall across the large end of its expansion chamber portion through which the inlet portion of the next succeeding element is disposed and secured, there being an annular space between the inlet portions and the surrounding expansion chamber portions, the forward end of each succeeding inlet portion being closed, the side walls of said inlet portions being provided with a plurality of inlet openings.
